United States Patent

Des. 237,980

Patented Dec. 9, 1975

237,980

CATTLE FEEDER

George Doyle Clugston, P.O. Box 581, R.R. 3,
Pittsburg, Kans. 66762

Filed Aug. 30, 1973, Ser. No. 392,973

Term of patent 14 years

Int. Cl. D30—03

U.S. Cl. D30—13

Fig.1.

Fig.2.

Fig. 3.

FIG. 1 is a perspective view of a cattle feeder showing my new design;

FIG. 2 is a perspective view of the support member, the container and hood being omitted for convenience of illustration; and

FIG. 3 is a front perspective view of the cattle feeder.
I claim:

The ornamental design for a cattle feeder, substantially as shown and described.
